(57) CLAIM

The ornamental design for grate, as shown and described.

DESCRIPTION

FIG. 1 is a perspective view of the grate embodying the new design;

FIG. 2 is a plan view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a perspective view thereof, showing the remaining segments of an assembled grate in broken lines; and,

FIG. 8 is a plan view thereof, showing the remaining segments of an assembled grate in broken lines.

FIGS. 1–8 show portions of a grate and an assembled grate in broken lines. The broken lines are shown for environmental purposes and form no part of the claimed design.
